UNITED STATES PATENT OFFICE.

THOMAS H. KNAPP, OF CHICAGO, ILLINOIS.

SPACE-BAND FOR LINOTYPE-MACHINES.

1,078,049.

Specification of Letters Patent.

Patented Nov. 11, 1913.

Application filed April 23, 1913. Serial No. 763,116.

To all whom it may concern:

Be it known that I, THOMAS H. KNAPP, a citizen of the United States, residing at Chicago, in the county of Cook and State 3 of Illinois, have invented a certain new and useful Improvement in Space-Bands for Linotype-Machines, of which the following is a specification.

This invention relates to matrix setting 19 machines and particularly to the space bands of linotype machines, particularly those of the type now in extensive use, manufactured by the Mergenthaler Linotype Company.

15 In matrix setting by machinery and particularly by the aid of the machines above mentioned, the machine is provided with a plurality of type matrices which are, on pressing the keys of the machine, released 20 down into an assembling device. When the operator reaches the end of a word, he presses a key which feeds down, adjacent to the last matrix, a space band, the details of which will be hereafter described. When 25 the matrices and space bands for all the words of a single line are in place, the space bands are, at some particular point in the machine, simultaneously manipulated to justify or, in other words, completely space 30 the entire line. In actual practice the matrices containing the dies for the type are made of brass, while the space bands have to be made of the strongest possible material which is a high grade steel, this be- 35 cause in the first place, they have to fall about thirteen or fourteen inches at one point in the machine and also have to be repeatedly and accurately manipulated in justifying successive lines in which they are 40 repeatedly used. If these space bands were made of any soft and easily wearable material like brass or copper, their life would be so short that the expense would be prohibitive, for such soft metal could not pos- 45 sibly stand the hard usage to which these parts are subjected.

In a machine of the class described, when the plurality of matrices and interposed space bands have been justified to form a 50 line, they are presented to a casting machine which casts soft metal in the form of the type dies on the successive matrices. The type metal does not adhere to the matrices but it is found in practice that it does re- 55 peatedly adhere to the sides of the steel space bands so that in the course of a day's

run of a machine of the class described, during which time each space band is used in many different lines of type, the band acquires a gradually increasing little mountain of type metal on its side which makes 60 the band too wide and causes it to improperly space the matrices with resulting crushing of the adjoining matrix when the pressure for locking up the matrices and space 65 bands is exerted in the ordinary manner by the machine. This accumulating of type metal on the sides of the space bands, therefore, thus has a tendency to destroy the matrices which come in contact with a space 70 band so loaded with type metal and in addition to this, the metal on the space band at one point may leave a little crack at each side of it between the space band and the matrix in which, when the type casting op- 75 eration takes place, type metal may flow and thus cast a little "hair line or bur" adjacent to the letter formed by the die on the matrix which is adjacent to the space band. Again when two matrices have in a previous 80 setting of a line been crushed in the manner described, i. e., crushed on their sides or edges which come adjacent to the type line, and they are, in setting a following line, set in proximity to each other, there is obviously 85 formed a space or hole between these crushed matrices in which there is again cast a "hair line or bur" which is a defect in the cast line made by the machine. This defect is well described in a circular issued by the 90 linotype company calling attention to the necessity of repeated cleaning of the space bands as follows: "The hot metal, being cast repeatedly against the small wedges, has a tendency to adhere to them. In time 95 the accumulation of metal forms a slight protuberance which, if permitted to remain, will break in the side wall of the adjacent matrix, thus forming a depression into which metal will flow the next time that 100 matrix is used. This will result in raised fins or burs on the face of the slug between the letters, which are bound to show as hair lines on the printed page, giving it a blurred appearance." This is a very serious defect 105 with machines of this class and it is necessary to either employ one man to do nothing but visit successive machines, take out all the space bands and with proper tools clean the accumulated type metal from the sides 110 of the space bands, or it is necessary for the high priced operator of the machine to him-

self stop the machine and do this. In either case considerable expense is involved both in the wages of the employee and the loss of time of the machine itself. This is, however, not all of the damage or expense created by this accumulation of metal upon the space bands for when the matrices or any considerable number of them have been thus crushed in the manner described, they are entirely worthless even for the most careless and least painstaking, small country printing office and as the matrices at the present market cost \$75.00 a set, it will be seen that this is a serious matter.

The object of this invention is to modify the construction of the space bands of the type described so that while maintaining the necessary strength and fine adjustment which they must possess, the accumulation of type metal in the manner described is entirely done away with, with the resulting elimination of substantially all of the losses above enumerated.

The invention consists in a device capable of carrying out the foregoing objects which can be easily and cheaply made and satisfactorily operated to accomplish the desired result and is not readily liable to get out of order.

It more particularly consists in modifying the space band of the required high strength metal by inserting right at the point where the type metal accumulates a piece of another metal which does not have the property which steel has of accumulating type metal.

It also consists in other features which will be more fully set forth in the specification and claims.

In the drawings in which similar numerals indicate the same parts throughout the several views, Figure 1 is a perspective view of a space band now commercially in use in the linotype machines of the class described, to which my invention in its preferred form has been applied. Fig. 2 is a face view of a plurality of matrices set in position ready for use, one of the devices of my invention being inserted between the two words "New" and "York." In Fig. 3 is shown one of the devices of the prior art having the objectionable accumulation of type metal thereon which causes all the damage and expense above set forth.

The space band proper consists of what is technically called a sleeve 10 having slidably mounted on its back a wedge 12. The method of securing these two parts in operative sliding position forms no part of this invention and is, therefore, not shown. The device is, however, so constructed that the front face of the sleeve and the rear face of the wedge are always parallel to each other in all positions of the wedge. The wedge is, as shown, thinner at its top than

at its bottom so that when it is shoved upward from the position shown in the figures along the sleeve, the combined thickness of the space band, *i.e.*, the sleeve and wedge, at any point in the sleeve will be greater than is shown in Figs. 1 and 2 and correspondingly when the wedge is moved downward with reference to the sleeve the thickness of the space band will be less.

The linotype machine heretofore described is provided with a track or as is known in the art "rails" on which these space bands are suspended by ears 14 extending from opposite sides of the sleeve and when the linotype machine releases the space band from the "space band box," the space band drops some thirteen or fourteen inches to the "assembling rails" and is caught and stopped by the engagement of these ears 14 with the "assembling rails" except as the fall may be checked somewhat by a buffer provided to catch the lower ends of the space bands as they strike the "assembling rails." The wear on these ears is, however, terrific due to this usage and the ears at least must, therefore, be made of as strong material as possible which so far as is known at the present time is of a high-grade tempered steel. Again, the minimum thickness of the space band is normally less than three sixty-fourths of an inch in thickness, and as the wedge has to be moved up along the sleeve 10 under considerable side pressure every time a line of matrices is set as shown in Fig. 2, it is evident that these relatively thin parts must be made of high resistance material in order to do away with undue wear.

In Fig. 2 is shown a plurality of matrices 16 as they appear with the space band between them ready to have type cast from the letters which appear upon the faces of the matrices.

As heretofore fully explained, in a device of the prior art a little mountain or pile of metal 20 accumulates, as shown in Fig. 3, on the side of the sleeve adjacent to the matrix which happens to come in contact with it and this defect is cured in the device of this invention by inserting in the sleeve at this point a piece of soft metal 22 preferably brass or copper, which has no affinity for type metal. This insert 22 is made of such a depth that it extends just back of the die in the adjacent matrix 16 and of a length a little longer than the height of the tallest letter which is apt to come adjacent to it, thereby weakening as little as possible the sleeve of the space band.

Type metal does not accumulate on the right hand side of the wedge 12 as viewed in the figures, for the reason that it is frictionally rubbed against the adjacent matrix, in the particular case here illustrated that of the letter "W," in being forced up to just

tified position. In addition to this, the wedge almost never has its same portion presented to the adjacent letter to be cast as different lines will, when justified, leave the wedges 5 in different positions.

The insert 22 may be secured in the position shown in the sleeve 10 of the space band by any suitable means, the exact means of securing it in place being no part of this invention.

When "two-letter matrices" are used instead of the one letter type shown in the drawings, it is only necessary to make insert 22 of corresponding length so as to protect 15 the sleeve at the point where it contacts each letter of the matrix.

Having thus described my invention, what I claim as new and desire to secure by Letters Patent, is:

20 1. A space band, for insertion between two matrices containing type dies, in which the body of the space band is made of strong wear resisting material, there being inserted at the point where, in the use of the device, 25 the space band comes in contact with the die of the adjacent matrix, a piece of material to which type metal does not readily adhere.

2. A space band comprising a "sleeve" and a "wedge" therefor, the space band being 30 made of material selected for its strength and wear resisting qualities, said sleeve be-

ing provided with a relatively small insert of material to which type metal does not ordinarily readily adhere, said insert being located in the sleeve at that point where, in 35 the ordinary use of the space band, type metal would adhere.

3. In a device of the class described, a space band comprising the sleeve 10 and the wedge 12 operatively connected thereto, said 40 sleeve 10 being provided in the edge where, in its use, it is normally contacted by type metal, with an insert 22 of a material to which type metal does not readily adhere, all of the parts being arranged and disposed 45 as shown and described for the purposes set forth.

4. A space band for insertion between two matrices containing type dies, in which the body of the space band is made of strong 50 wear resisting material, there being inserted at a point where in the use of the device the space band comes in contact with the die of the adjacent matrix, a piece of brass or copper, for the purposes set forth.

In witness whereof, I have hereunto subscribed my name in the presence of two witnesses.

THOMAS H. KNAPP.
